UNITED STATES PATENT OFFICE.

EDWARD GUY GOBEN, OF NEW ORLEANS, LOUISIANA, ASSIGNOR TO THE E. V. BENJAMIN COMPANY, INC., OF NEW ORLEANS, LOUISIANA, A CORPORATION OF LOUISIANA.

FOLDING MACHINE.

Application filed October 9, 1924. Serial No. 742,619.

This invention relates to a folding machine and the method of folding pieces of material. The invention is an improvement of the machine described in United States Letters Patent No. 1,482,605, dated February 5th, 1924.

The object of the present invention is the production of a folding machine in which pieces of fabric, cloth or other material are manually fed thereto, and all folded in a similar manner.

The present invention differentiates from Letters Patent No. 1,482,605 in that automatic actuated means are provided to locate the pieces of material to be folded in proper position when they are fed to the machine. The present invention also provides means for bringing the loose ends of the material together as they are released from the machine before being doffed. Other objects will be apparent from the following description and claims.

In the accompanying drawings Fig. 1 represents a side elevation of an exemplification of the improved folding machine; Fig. 1^a is a right hand side view of some details of Fig. 1; Fig. 2 shows a top plan view of Fig. 1 with a fragmentary portion of one end omitted; Fig. 3 indicates an enlarged section of a portion of Fig. 2 on the line 3, 3; Fig. 4 represents a top plan view of Fig. 3; Fig. 5 shows an enlarged section of Fig. 2 on the line 5, 5; Fig. 6 is an enlarged section of Fig. 2 on the line 6, 6; Fig. 7 shows a top plan view of Fig. 6; Fig. 8 shows an enlarged fragmentary portion of Fig. 1; Fig. 9 shows a top plan view of Fig. 8; Fig. 10 indicates an elevation of a detail; Fig. 11 is a left hand side view of Fig. 10, and Fig. 12 shows a section of Fig. 8 on the broken line 12, 12.

The improved folding machine in this exemplification comprises a pair of similar side frames 20 and 21, which are positioned in place by separator bolts 22. A pair of knee brackets 23 extend from each of said side frames. Each pair of said brackets supports an operating platform 25.

A pair of similar table frames 26 are supported upon and bolted to the frames 20 and 21. Separator bolts 27 are connected to the frames 26. A feed table preferably of wood comprises the sections 28 and 29 which are hinged to one another by means

of hinges 30. The sections 28 and 29 are supported upon and fastened to the frames 26.

A pair of similar journal brackets 35 and 36 are supported upon and bolted to the side frames 20 and 21. Each of the brackets 35 and 36 has extending therefrom the V shaped members 37, and at the peaks of the latter are journal bearings 38. Journal bearings 40 and 41 are provided for the journal brackets 35, 36. A receiving drum shaft 45 is journaled in the journal bearings 40 and a delivery drum shaft 46 is journaled in the journal bearings 41.

A plurality of receiving wheels 50 with the rims 51 are adjustably connected to the shaft 45, by means of the set screws 52. Each of said wheels has formed therewith the annular slot 53. A folding bar 55 with the folding rib 56 is connected to the rims 51 of the receiving wheels 50. The wheels 50 in their aggregate constitute the receiving drum of the machine.

A spur gear 58 is fastened to the shaft 45 adjacent to the journal bracket 35. Bolts 60 and 61 extend through the wheels 50 and 80 the spur gear 58 to turn them in unison.

A wheel 65 is fastened to the shaft 45 by means of the set screw 66.

A stationary cam 68 with the cam surface 69 has formed therewith the supporting arm 70. The latter is bolted to the journal bracket 36 by means of bolts 71.

A shaft 75 extends through the slots 53 of the receiving wheels 50. A plurality of arms 76 have one end of each fastened to the shaft 45, by means of the set screws 78, and the shaft 75 extends through the other ends of said arms. A lug 79 with the flexible buffer block 80 extends from one face of each of the arms 76. Grippers 81 are fastened to the shaft 75. Each of the said grippers coacts with one of the buffer blocks 80. On the shaft 75 adjacent to the cam 68 is fastened a bell crank with the arms 82 and 83. To the end of the arm 82 is journaled a roller 84 and to the end of the arm 83 is pinned one end of the rod 85, which is threaded at one end as indicated at 86. A guide bracket 87 extends from the wheel 65 and guides one end of the rod 85. The roller 84 coacts with the cam surface 69 of the cam 68.

On the shaft 45 is fastened the cam 92.

In the journal bearings 38 of the members 37 is supported an oscillating shaft 93, which has fastened to one end thereof the arm 94. A link 95 has one end pinned to the arm 94 and at its other end is journaled a roller 96 which coacts with the cam surface of the cam 92. A helical spring 97 encircles the shaft 93 and has one end fastened to the side face of the journal bracket 35. The other end of the spring 97 is fastened to the collar 98, which latter in turn encircles the shaft 93 and is fastened to the same. The tension of the spring 97 maintains the roller 96 in contact with the cam surface of the cam 92. A block 99 is formed with and extends from one of the V shaped members 37 and has extending therefrom the guide 100, which maintains the link 95 in proper position. A plurality of brackets 105 are fastened to the shaft 93 and have connected thereto the adjusting fingers 106. A spur gear 110 is fastened to the shaft 46 and meshes with the spur gear 58.

A plurality of delivery wheels 112 each with an opening 113 in its rim are fastened to the shaft 46, by means of set screws 113^a and are respectively in alignment with the receiving wheels 50. The wheels 112 in the aggregate constitute the delivery drum. A shaft 114 connects all wheels 112 and the spur gear 110, so that they turn in unison. A cam 115 has extending therefrom the bracket 116, which latter is fastened to the journal bracket 35 by means of the bolts 118. An oscillating shaft 120 is journaled in the delivery wheels 112 and in the spur gear 110.

A crank arm 122 has one end fastened to the shaft 120 and to its other end is journaled a cam roller 123 which coacts with the cam surface of the cam 115. A plurality of arms 124 have each one end fastened to the shaft 120 and extend into the opening 113. The other ends of the arms 124 is fastened in the pinching bar 125. A strip of flexible material 126 is fastened to the bar 125. A second pincher bar 130 is fastened to the wheels 112 and has fastened thereto the strip of flexible material 131. A spring 132 has one end fastened to one of the arms 124 and its other end is fastened to the rim of wheel 112 adjacent thereto. The tension of the spring 132 maintains the roller 123 in contact with the cam surface of the cam 115.

A tight pulley 135 is fastened to the shaft 45 and a loose pulley 136 is journaled on said shaft. A belt 137 is provided for said pulleys. A shifter loop rod 140 has one end pivoted to the bracket 141 extending from the side frame 21, and has in turn pinned thereto one end of the shifter rod 141 having the operating handle 142.

To each of the side frames 20 and 21 is

fastened an angle bracket with the horizontal leg 146 having the elongated opening 147 and the inclined leg 149 with the flange 150. A baffle plate 151 with the curved ends 152 has formed at its ends elongated openings 153. Studs 154 extend from the flange 150 through the openings 153. The studs 154 are provided with the thumb screws 155. The baffle plate 151 can be adjusted to different positions on the flanges 150. A supporting arm 160 with an elongated opening 161 is adjustably fastened to each of the legs 146. A triangular shaped landing block 165 is bolted to the upper ends of the supporting arms 160.

To operate the folding machine the pieces of material D to be folded are located upon the feed table having the portions 28 and 29, and are one at a time located by the operator, upon the feed plate 32 with one end of each bearing against the adjusting fingers 106, to locate them in proper position upon the receiving drum, consisting of the receiving wheel 50. The pulley 135 is turned by the belt 137 and through the spur gears 58 and 110, the receiving drum is turned in the direction of the arrow A, and the delivery drum with its wheels 112 is turned in the direction of the arrow B. The grippers 81 of the receiving drum clamp one end of each piece of material D and carries it for a portion of each rotation of the receiving wheels. The arms 76 with the grippers 81 can be located in proper position to suit different lengths of cloth or other material to be folded, by loosening the set screws 78 and swinging the wheels 50 until the circumferential distance between the folding rib 56 and the buffer block 80 equals one half the length of each piece of material to be folded after which the set screws are again tightened in place. By the coaction of the roller 84 and the cam 68 the grippers 81 are opened and closed at the proper time.

As the pieces of material are carried upon the receiving drum, the folding rib 56 will engage the middle portion of each, and they are brought with their middle portions opposite the openings 113 of the delivery wheels 112, which occurs when a plane passing through the axes of the shaft 45 and 46 is reached by the folding rib 56. At this instant the coaction of the cam roller 123 with the cam 115 causes the pinching bar 125 to swing to its closed position and the pieces of the material D are drawn from the wheels 50 and brought to the position indicated at D', then D² folded with a crease. The pieces of material with their folded portions strike the baffle plate 151 and take the position D³ with their suspended portions bearing against each other. The folded pieces of material are next released from the delivery drum and doffed one after the other on the landing block shown at D⁴.

The adjusting fingers 106 by the coaction of the cam 32, roller 96 and the parts connected thereto are located just above the circumferential surfaces of the receiving 5 wheels 50 with the ends 107 at the sides of the wheels, as the operator places the pieces of material in proper position upon the receiving wheels.

Having described my invention what I 10 desire to secure by Letters Patent and claim is:

1. In a folding machine the combination of a rotatable receiving drum, a rotatable delivery drum adjacent thereto, means to 15 rotate the drums in unison, means to feed pieces of material to be folded to the receiving drum, automatically actuated grippers for the receiving drum to clamp one end of each piece of material thereto for a 20 predetermined portion of each revolution thereof, automatically actuated pinching means on the delivery drum to remove each piece of material from the receiving drum at an intermediate portion of each piece of 25 material between its ends, forming a crease therein, each piece of material suspended from the delivery drum at said crease during a portion of each rotation thereof with portions of each piece suspended from its 30 crease, a baffle plate below the drums in the path of the portions of the pieces of material to force them together and a landing block adjacent to the baffle plate to receive the folded pieces of material as they 35 are doffed from the delivery drum.

2. In a folding machine the combination of a pair of frames, a rotatable receiving drum and a rotatable delivery drum adjacent thereto, means to journal both drums to 40 said frames, means to rotate the drums in unison, means to feed pieces of material to be folded to the receiving drum, automatically actuated grippers for the receiving drum to clamp one end of each piece of 45 material thereto for a predetermined portion of each revolution thereof, automatically actuated pinching means on the delivery drum to remove each piece of material one after the other from the receiving drum at an intermediate portion thereof between its ends forming a crease in each 50 piece of material, each piece of material suspended from the delivery drum at said crease during a portion of each rotation thereof with portions of each piece of material suspended from its crease, a pair of 55 angle brackets each with an inclined leg fastened to said frames under the drums, a baffle plate adjustably supported by the 60 said inclined legs, a supporting arm adjustably connected to each of said angle brackets, said baffle plate in the path of the

pieces of material to force them together and a landing block connected to said supporting arms to receive the folded pieces 65 of material as they are doffed from the delivery drum.

3. In a folding machine the combination of a pair of frames, a rotatable receiving drum and a rotatable delivery drum adjacent thereto, means to journal both of said drums to the frames, means to rotate the drums in unison, a feed table supported on said frames, for pieces of material to be folded, a feed plate extending from the 70 feed table to the receiving drum, automatically actuated adjusting fingers over the receiving drum for the ends of pieces of material operated upon to bear against as they are fed from the feed plate to the receiving 75 drum, means to clamp one end of each piece of material to the receiving drum for a portion of each rotation thereof and means for the delivery drum to release each piece of material from the receiving drum. 80

4. In a folding machine the combination of a pair of frames, journal brackets supported on the frames, said journal brackets having members extending therefrom with journal bearings, a pair of shafts journaled 90 in said brackets, a receiving drum fastened to one of said shafts and a delivery drum fastened to the other shaft, means to rotate said shafts in unison, a feed table supported on said frames for pieces of material to be folded, an oscillating shaft supported in the journal bearings in said 95 members extending from said journal bearings, a plurality of adjusting fingers in connection with the latter shaft adapted to approach the circumferential surface of the receiving drum, a cam fastened to and rotating with the shaft of the receiving drum, an arm with one end fastened to the oscillating shaft, a link with one end pinned to the other end of said arm, a roller journaled to the other end of said link, said roller coacting with said cam, means to guide said link, a spring with one end fastened to one of said members extending from the journal brackets and the other end in connection with said oscillating shaft, said adjusting fingers for the 100 ends of pieces of material to be folded to bear against as they are fed to the receiving 105 drum, means to clamp one end of each piece of material to the receiving drum for a portion of each rotation thereof and means for the delivery drum to release each piece of material from the receiving drum. 110

Signed at New Orleans in the parish of Orleans and State of Louisiana this 16th day of September A. D. 1924.

EDWARD GUY GOBEN.
